[57] ABSTRACT

The ventilator has a closure member swingable against one side of a wall at opposite sides of an opening therein and held in selected position by the force exerted by a spring rod against the wall's opposite side. Double-bracketed guide members receiving and restricting radial movement of opposite end portions of the rod in guideways between inner and outer fixed brackets and cooperating stops on and limiting relative axial movement of the rod, render the ventilator fail-safe under excessive twisting forces.

TWO-WAY HINGELESS VENTILATOR

BACKGROUND OF THE INVENTION

In a hingeless ventilator of the type disclosed in Kelly et al. U.S. Pat. Nos. 3,102,464 and 3,358,576, a frame fits about an opening in the wall of a truck cab or other enclosure to be ventilated and has an outturned flange bounding the opening. The ventilator's closure member has an inturned peripheral flange fitting in that member's closed position about the outturned flange on the frame. Opening in opposite directions by swinging against the frame at either side of the opening, the closure member is held assembled and in any selected position by a spring rod connected to and swingable with the member and acting against guideways fixed to and instanding from the frame on the other side of the wall and at opposite ends of the opening. The closure member has its swinging axis on either side of the opening substantially fixed by engagement of a side of its inturned flange with the corresponding side of the outturned frame flange and the force applied by the spring rod is made substantially uniform by forming each guideway of cylindrical side sections each substantially concentric with the opposite swinging axis.

The two-way ventilators of the Kelly et al. U.S. Pat. are intended to be swung manually and, when so swung, operate very effectively. However, in some installations the ventilator is in easy reach of the foot of the operator with the consequent tendency to move the closure member to the desired position by kicking the spring rod or a separate handle. In such case, not only is the force excessive, but the rod can be twisted so that one end is on the wrong side of its guideway relative to the then swinging axis, with resultant jamming and at least temporary failure of the ventilator. It is to a solution of this problem that the present invention is particularly directed.

SUMMARY OF THE INVENTION

The primary object of the present invention is to provide an improved two-way hingeless ventilator in which ends of a spring rod holding a closure member in selected position are so guided as to render the ventilator fail-proof under excessive twisting forces.

Another object of the present invention is to provide an improved two-way hingeless ventilator of the type described in the preceding object, wherein failure of the ventilator under excessive twisting forces is prevented by guiding and radially containing each end of the spring rod in a guideway between inner and outer guide brackets and limiting axial movement of the rod relative to the guide brackets.

Other objects and advantages of the invention will appear hereinafter in the detailed description, be particularly pointed out in the appended claims and be illustrated in the accompanying drawings, in which:

FIGURE DESCRIPTION

FIG. 1 is an inner plan view of a preferred embodiment of the improved two-way hingeless ventilator of the present invention;

FIG. 2 is an inverted end elevational view of the ventilator of FIG. 1;

FIG. 3 is a fragmentary sectional view taken along lines 3-3 of FIG. 1;

FIG. 4 is a sectional view taken along lines 4-4 of FIG. 1;

FIG. 5 is a fragmentary sectional view on an enlarged scale taken along lines 5-5 of FIG. 1, and

FIG. 6 is a fragmentary sectional view on the scale of FIG. 5, taken along lines 6-6 of FIG. 3.

DETAILED DESCRIPTION

Referring now in detail to the drawings in which like reference characters designate like parts, the improved two-way hingeless ventilator of the present invention is of the same type as those disclosed in Kelly et al. U.S. Pat. Nos. 3,102,464 and 3,358,576 and also designed primarily for application to a cab or other enclosure of a vehicle for directing air into or from the enclosure when the vehicle is moving.

As do the ventilators of the above patents, the improved ventilator of this invention has as its main components a frame 1 fixed to an outside wall 2 of the vehicle cab or other enclosure (not otherwise shown) and bounding a generally rectangular opening 3 in the wall, a closure member or cover 4 seatable against an outer side of and swingable on the frame for opening and closing the opening, spaced guides 5 fixed to and instanding from an inner side of the frame at opposite ends of the opening, and a guide rod 6 connected centrally to the closure member and having ends riding along the guides for holding the closure member assembled and in any selected position relative to the frame.

The improved ventilator also resembles the ventilators of the Kelly et al. U.S. Pat. in being openable in two ways or directions by swinging its closure member 4 against the frame 1 at either side of the opening and conveniently making use in its preferred embodiment of side portions of an outturned or outstanding lip or flange 7 on the frame about the opening and a surrounding, inturned or instanding peripheral skirt or flange 8 on the closure member for substantially fixing the swinging axes of the closure member. Further, as in U.S. Pat. No. 3,358,576, the spring rod 6 preferably is releasably connected at the center to the center of the closure member 4 by a hook 9 fixed to and instanding from the latter and the closure member conveniently is swung by a separate U-shaped handle rather than by the spring rod 10, the handle having legs 11 fixed to and instanding from the closure member and straddling the hook and being longitudinally slotted to pass and accommodate flexing of the rod.

Similar in its preferred embodiment to the ventilators of the Kelly et al. patents in the foregoing respects, the improved ventilator of the present invention differs therefrom in having as its spaced rod guides 5 a pair of double-bracketed guides or guide members. Each guide member 5 is formed of inner and outer guide brackets 12 and 13, respectively, each of which is a generally U-shaped band of substantial width or breadth, footed, as at 14, at its inner extremities for fixing to the frame 1 and conveniently made by stamping or otherwise bending a sheet metal strip of the desired width and thickness. Aligned radially of the rod 6 and normal to the frame 1, the inner and outer brackets 12 and 13 of each guide member 5 are laterally spaced inwardly or inboardly of the frame 1 and together bound inner and outer sides of a generally U-shaped guideway 15 extending uninterruptedly between their feet 14 and receiving and radially containing the adjoining end portions of the rod.

The guide members 5 are a counterpart or duplicate and spaced longitudinally of and centered laterally on

the frame 1 and the inner and outer guide brackets 12 and 13 of each have preferably as a whole and at least along their confronting faces or surfaces substantially cylindrically, oppositely facing or opposite side portions 16 and 17, respectively, each of which is substantially concentric with and swung or struck about the swinging axis of the closure member 4 at the opposite side of the frame. The side portions 16 or 17 of each guide bracket merge at the center in arcuate center or mid-portions, designated as 18 for the inner brackets and 19 for the outer brackets, which, although of different curvature, suitably are also convex in a direction away from the frame. With the inner and outer brackets 12 and 13 of each guide member 5 so curved and the guideway 15 therebetween of substantial width and substantially uniform depth, the end portions of the rod 6 received in the guideways ride on the inner brackets at a pressure predetermined by the outward flexure of the rod at the center toward the closure member 4 and are limited by the enclosing or overlying outer brackets.

Open longitudinally of the frame 1 to both receive and pass the end portions of the rod 6, the preferred guideways 15, while of a depth to accommodate the slight relative angling of the end portions of the flexed rod, are intended otherwise to have a fairly snug sliding fit therewith. To achieve this without binding or undue hindrance of wear from metal-to-metal contact, the rod 6 preferably does not directly contact the inner and outer brackets and, instead, is spaced radially from the brackets by a bushing or bearing 20, suitably made of "NYLATRON" or like wear-resistant, anti-friction material, each of the preferred bushings 20 has a stem 21 fitting with the desired snugness in and extending across the adjoining guideway 15, and an enlarged head 22 integral with the stem and outside or outboard of and radially overlapping the adjoining inner and outer brackets. Bearing against the confronting outer edges of the adjoining brackets 12 and 13, preferably through an interposed metal washer 23 to minimize grooving and distribute stresses, each head 22 is held or restrained against substantial axial movement along the rod 6 on the inside by the brackets and the outside by a suitable retainer, such as illustrated snap ring 24. In turn, the heads 22 on opposite ends of the rod 6 both locate or position the bushings 20 and inhibit or prevent substantial axial movement of the rod relative to the guide members 5.

Substantially restricted or restrained outward radial movement relative to the inner brackets 12 by the outer brackets 13 and against axial movement relative to the guide members 5 by the heads 22, the rod 6 cannot be twisted or canted so as to shift or move either end portion to the wrong side of the adjoining inner bracket, regardless of the force applied in operating the ventilator. Thus, even the large twisting force produced by a heavy kick or blow delivered to the handle 10 toward either end thereof is incapable of jamming the ventilator by correspondingly twisting the rod relative to either or both of the guide members and the ventilator will remain operative in service short of actual physical destruction.

From the above detailed description it will be apparent that there has been provided an improved two-way hingeless ventilator that is proof against failure under intentional or accidental misuse. It should be understood that the described and disclosed embodiment is

merely exemplary of the invention and that all modifications are intended to be included that do not depart from the spirit of the invention and the scope of the appended claims.

Having described my invention, I claim:

1. A two-way hingeless ventilator for ventilating an enclosure through a wall thereof, comprising a frame fixable to said wall and bounding an opening there-through, a closure member on an outer side of said frame and alternately swingable thereagainst at opposite sides of said opening for opening and closing said opening, cooperating means on said frame and closure member for substantially fixing the swinging axes of said member, a spring rod on an inner side of said frame and extending longitudinally of said opening, said spring rod intermediate ends thereof being connected to and flexed toward said closure member for swinging therewith and holding said member against said frame, double-bracketed guide members fixed to and instanding from said inner side of said frame at opposite ends of said opening, each guide member including an inner guide bracket on which an adjoining end portion of said rod rides and is guided during swinging of said closure member and acts in holding said closure member in a selected position, and an outer guide bracket overlying and inwardly of said frame laterally spaced from said inner bracket and therewith bounding inner and outer sides of a guideway, said outer guide members radially containing and restricting said end portions against substantial outward radial movement relative to said inner guide members, and means on and projecting radially from said rod and overlapping and acting axially of said rod against said guide members for restricting said rod against substantial axial movement relative thereto, said outer guide members and axially acting means cooperating for preventing excessive forces from twisting one end portion of said rod to a wrong side of the adjoining inner guide member relative to the then swinging axis.
2. A ventilator according to claim 1, wherein the guide members are counterpart and substantially centered laterally on the opening, confronting surfaces of the inner and outer guide brackets of each guide member at opposite sides of the guideway are generally U-shaped, and each surface has on each side thereof a substantially cylindrical side portion substantially concentric with an opposite swinging axis of the closure member.
3. A ventilator according to claim 2, wherein the guide brackets are bands of substantial width having at opposite extremities thereof feet fixed to the frame, and said bands between said extremities are arcuately convex in a direction away from the frame.
4. A ventilator according to claim 2, wherein the restricting means on the rod include a bushing on each end portion having a stem received in and extending across the related guideway and a head radially overlapping and acting against confronting surfaces of the adjoining guide brackets, and retaining means on the rod at opposite sides of the head from the guide brackets.
5. A ventilator according to claim 4, wherein the guideways are open-sided axially of the rod, each end portion of the rod extends through the adjoining guideway, and the heads and retaining means are outside the guide brackets.
6. A ventilator according to claim 5, wherein the bushings are of wear-resistant anti-friction material, and including washers on the rod and each interposed between a bushing head and the adjoining guide brackets.
